CHAIR

Gunter F. Ris, Oberpleis, Siegburg, Germany, assignor to Rosenthal Aktiengesellschaft, Selb, Bavaria, Germany

Filed Apr. 14, 1971, Ser. No. 134,119

Term of patent 14 years

Int. Cl. D6—02

U.S. Cl. D6—26

FIG. 1 is a view in side perspective of a chair showing my new design with the cover thereof in closed position;
FIG. 2 is a view in rear perspective;

FIG. 3 is a view in side perspective with the cover partially opened;

FIG. 4 is a view in front perspective of the chair of FIG. 3;

FIGG. 5 is a side perspective view of the chair in fully opened position;

FIG. 6 is a front perspective view thereof; and

FIG. 7 is a front perspective view of the chair of FIG. 1 in fully opened position and wherein the seat is provided with an upholstered back rest portion as shown.

I claim:

An ornamental design for a chair, as shown and described.
